US00D733088S

(12) **United States Design Patent**
Garneau et al.

(10) **Patent No.:** **US D733,088 S**
(45) **Date of Patent:** **** Jun. 30, 2015**

(54) **JUKEBOX STAND**

(71) Applicant: **TouchTunes Music Corporation**, New York, NY (US)

(72) Inventors: **Charles Garneau**, Bois-des-Filion (CA); **Benoit Tessier**, Boisbriand (CA); **Ed Rivera**, New York, NY (US); **Michael Tooker**, Montreal (CA); **Jinseok Hwang**, Palisades Park, NJ (US); **Jonas Damon**, New York, NY (US)

(73) Assignee: **TouchTunes Music Corporation**, New York, NY (US)

(**) Term: **14 Years**

(21) Appl. No.: **29/486,234**

(22) Filed: **Mar. 27, 2014**

Related U.S. Application Data

(62) Division of application No. 29/461,532, filed on Jul. 24, 2013, now Pat. No. Des. 704,160, which is a division of application No. 29/446,838, filed on Feb. 27, 2013, now Pat. No. Des. 689,461, which is a division of application No. 29/433,240, filed on Sep. 27, 2012, now abandoned, which is a division of application No. 29/401,854, filed on Sep. 16, 2011, now Pat. No. Des. 670,675.

(57) **CLAIM**

The ornamental design for a jukebox stand, as shown and described.

DESCRIPTION

FIG. 1 is a front perspective view of a jukebox stand showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof; and,

FIG. 8 is a rear perspective view thereof.

The broken lines indicate unclaimed portions and form no part of the claimed design.

1 Claim, 7 Drawing Sheets
